CLAIM

The ornamental design for a carrier rack for housing a cooler when attached to a golf cart, as shown and described.

DESCRIPTION

FIG. 1 is a top, front and left side perspective view of a carrier rack for housing a cooler when attached to a golf cart showing my new design;

FIG. 2 is a front elevational view thereof;

FIG. 3 is a top plan view thereof; and

FIG. 4 is a left side elevational view, the right side being a mirror image thereof.

FIG. 1

FIG. 2

FIG. 3

FIG. 4
